AUTOMATIC LOCK SLIDER FOR SLIDE FASTENERS

William Mikulas, West Brighton, Staten Island, N. Y., and Lester L. Jones, Oradell, N. J., assignors to Cenmar Products Corporation, Newark, N. J., a corporation of New Jersey

Application March 3, 1945, Serial No. 580,750

19 Claims. (Cl. 24—205.14)

1

This invention relates to an improved automatic lock slider for slide fasteners.

Slide fasteners comprise two mating slide fastener stringers (tapes with mounted fastener elements) brought into and out of meshing or mating relation by the movement of a so-called slider through the slide channel of which the stringers slide or move. It is necessary to provide a suitable locking device for the slider to prevent the stringers accidentally opening during use. According to one type of lock slider, the locking device is made so as to be entirely automatic in its locking operation. The common form of automatic lock slider embodies a locking member on the slider which is normally held in its locking position by a spring or its equivalent.

Our present invention relates to an automatic lock slider for slide fasteners which is operative without the use of any spring; the automatic lock slider of our present invention embodies a new principle and mode of operation which depends solely for its automatic function upon the interaction between a locking member and the slide fastener stringers. The broad principles of this lock slider are disclosed and claimed in our Patent No. 2,360,437, patented October 17, 1944; and the present application relates to certain improvements in this new type of lock slider.

In the automatic lock slider of our Patent No. 2,360,437, the locking member comprises a two-armed lever fulcrumed on the slider, the arms of which project into the slider channel, one arm being in a position to act upon the fastener elements of the stringers to lock the slider, and the other arm being in a position to be acted upon by other of the fastener elements of the stringers to operate the locking member. A difficulty develops when such an automatic lock slider as disclosed in said patent is to be used with separable bottom stops or with top stops which are relatively long; for in such cases the termini of the arms of the locking member have to be simultaneously depressed in order to permit passage through the slider of the pin member of a separate bottom stop, thus interfering with such passage, or such termini interfere with the insertion of a relatively long top stop into the slider channel. The prime object of our present invention centers about the provision of an improved form of automatic lock slider of the type referred to in which this difficulty is solved.

It is a further object of the invention to so construct this form of automatic lock slider and particularly the locking member thereof that the force or forces causing the locking action is or are effectively increased. The locking member to be used in accordance with the present invention is rockably supported by the slider. It has been found that the provision of two different fulcra instead of one fulcrum for the locking

2

member makes the control of the latter easier. It is, therefore, another object of the present invention to so provide such fulcra for the locking member so that an easier and safe control of the locking and unlocking actions of the locking member is obtained and assured.

To the accomplishment of the foregoing prime objects and such other objects as may hereinafter appear, our present invention relates to the automatic lock slider and its component parts as sought to be defined in the appended claims and as described in the following specification taken together with the accompanying drawings in which:

15 Fig. 1 is a side view of an automatic lock slider embodying the principles of the invention, taken in cross-section in the plane of the line 1—1 of Fig. 2 and showing a portion of the pull member;

Fig. 2 is a front elevational view of same;

20 Fig. 3 is a view taken in cross-section in the plane of the line 3—3 of Fig. 2;

Fig. 4 is a side view taken in cross-section of the upper or front slider half used in the slider of Figs. 1 to 3 and showing that slider half before assembling;

25 Fig. 5 is a view of a part of the slider taken in cross-section in the plane of the broken line 5—5 of Fig. 2;

Fig. 6 is a side view of the locking member used in the slider shown in Figs. 1 to 3;

Fig. 7 is a front elevational view of same;

Figs. 8 and 9 are views of parts shown in cross-section on the lines 8—8 and 9—9, respectively, of Fig. 6;

30 Figs. 10A, 10B, and 10C schematically illustrate one kind of force causing the slider locking action; and

Fig. 11 is a side view of a modified slider.

Referring now more in detail to the drawings and having reference to the constructional form shown in Figs. 1 to 10C, and referring first to Figs. 1 to 3, the invention is shown applied to a conventional type of slide fastener comprising the slider S provided with the interior slide channel C and the two stringers, s, s, the latter each comprising a beaded tape t with the spaced slide fastener element f, f mounted thereon, the said stringers being adapted to be brought into and out of meshing or mating relation by the up and down movement of the slider S through the slide channel C of which the stringers slide or move. The slide channel C is a Y-shaped channel as best shown in Fig. 2 through the stem of which the fastener elements move when meshed

45 or interengaged and through the Y branches of which the fastener elements move when they are disengaged, as is most clearly shown in Fig. 2 of the drawings.

According to one form of known structure, the slider S comprises a top section or front slider

3

half 10 and a bottom section or lower slider half 12, spacedly connected to provide the slider channel C. This type of slider is reorganized and combined according to the present invention with the locking member 14. The slider halves 10 and 12 may be united at one end as by riveting, as can best be seen in Fig. 1. The front slider half 10 is formed with an opening 16 (see Fig. 2) for receiving the locking member 14. The latter is supported by a lug 18 on the outer wall of the front slider half and is rockable about the terminus 20 of the lug 18, this terminus 20 forming a fulcrum for the locking member. Under certain conditions, which will be discussed further below, the locking member 14 rests for support on the wall of the front slider half 10; and the under surfaces 22 of the locking member 14 being then in contact with the wall of the slider half, the locking member may also rock about the fulcrum 23 in the front wall surface 25 of the slider. The fulcrum 23 is not fixed but varies in the surface 25.

Following out the principles disclosed in our said Patent No. 2,360,437, the locking member 14 comprises a two-armed lever fulcrumed on the slider S having both of its arms projecting into the slider channel C, one arm of the lever terminating in a locking tooth (or teeth) and the other arm of the lever terminating in a point or surface of lever application. The fastener elements f, f, on the stringers s, s engage the point or surfaces of lever application to move or rock the lever locking member 14 about its fulcrum to cause the locking tooth to move into engagement with another fastener element on the stringers and thus automatically lock the slider, and means are provided consisting of the usual pull, for rocking the locking member in its opposite direction to disengage the locking tooth and move the slider in opening or closing direction.

In the improved structure of the present invention, the locking member 14 is a double-claw-shaped lever, one arm 24 of which terminates in two locking teeth 26, 26' arranged in staggered relation and the other arm 30 of which is provided with the end 28 to which forces are applied to urge the locking teeth into locking position. The stringers s, s, of the slide fastener run through the slider channel C in such a way that the locking teeth 26, 26' are on top or in front of the stringers and the end 28 of the arm 30 of the locking member is at the bottom or in the rear of the stringers. The locking tooth or teeth and the point or surface of lever application are thus, in this improved structure, on opposite sides of the stringers s, s. Also, as will be featured below, the area of application lies just behind the neck or so-called diamond of the slider, forming in effect a continuation thereof. This area of application is thus also localized centrally (along a median line) of the slider. These and other features described below produce the advantages which characterize the improved structure of the present invention.

The following is a detailed description of the individual slider-forming parts and of their assembly. Both the slider halves 10 and 12 and the locking member 14 are intended to be manufactured by die casting. Reverting now to Figs. 1 to 3 and also referring to Figs. 4 and 5, the front slider half 10 is provided with the opening 16 through its body, with lugs 18 and 34 at one side, with inturned side flanges 32 and 32' and a post 36 at the opposite side. The lugs 18 and 34

4

are cup-shaped as can be seen from Figs. 2 and 3, respectively. The post 36 (see Fig. 4) forms a hollowed rivet of non-circular shape (see Fig. 2) for riveting both slider halves together. The front slider half (see Fig. 2) is provided with two depressions each extending over the area between the lines D and D', the bottom of these two depressions sloping from D and D' toward E and E' and toward the opening 16, the most reduced bottom thickness below the depression being marked T in Fig. 5. As can be seen from Figs. 1 and 2, the lower or rear slider half 12 has inturned side flanges 42, 42' and is provided with a depression 44 and an opening 46, 48. In assembling the slider halves, the opening 46, 48 receives the rivet body 38 and protruding ring 40, respectively, of the post 36 of the front slider half, and the slider sections are riveted together.

The locking member 14 best shown in Figs. 3 and 6-9 comprises the aforesaid double-claw-shaped lever supported by the slider at the fulcrum 20 or 23 or both. The arm 24 of the locking member has an outer portion 49 which as is clearly shown in Figs. 3, 7, and 8 is wider than the web 50 thereof and which is designed to hold a pull tab 51 in position when secured to the locking member. The web 50 is accordingly adapted to receive the trunnions of the pull tab 51 which is thus in the usual way pendently attached to the locking member (Fig. 1). In Fig. 9, the cross-section of the other arm 30 of the locking member resembles the elevational view of a tent, the purpose of this peculiar shape being described hereinafter.

This slider and locking member are assembled by positioning the locking member 14 in the front slider half 10, it being inserted from the rear through the opening 16. Then the two slider halves 10 and 12 are riveted together. The arm 30 of the locking member is partly received in the depression 44 of the rear one of the slider halves or sections when these are united. The portion 49, in addition to holding the pull tab in place, also serves to prevent the locking member from collapsing when pounded down, as with an iron. As will be seen from Fig. 4, the hollowed rivet 36 is cast integrally with the front slider half. From a comparison of Fig. 4 with Fig. 1, it will be clear that the rivet body 38 is somewhat longer than the opening 46. The excess length and the protruding ring portion 40 are sufficient to expand and fill any space by which the rivet body 38 clears the rivet body opening 46 and the wider opening 48. After assembling, the portion 52 of the front slider half together with the portion 54 of the rear slider half form the so-called diamond or neck of the slider. The pull tab 51 is attached to the locking member either before or after inserting the same into the slider.

The function and operation of the slider is as follows: In the constructional form under discussion, the locking member, as shown in Fig. 1 in dash-dot lines, is in locking engagement. This dash-dot line locking position is held by the locking member while the slider is at rest and even if no force such as a cross-pull on the stringers is applied tending to open the slide fastener.

Upon moving the pull tab to the full line position and upon continuing the pull in the direction of the arrow X, i. e., in the slide fastener closing direction, the locking member 14 is rocked about its fulcrum 20 from the dash-dot line locking position to the full line unlocking position. Being now unlocked, the slider is free to move in closing direction. Upon moving the pull tab to

the dash-dot line position and on continuing the pull in the direction indicated by the arrow Y, i. e., in opening direction, the locking member 14 rocks about the fulcrum 23 and again swings from the dash-dot line locking position to the full line unlocking position. The locking member comes into contact with the slider at 56; and the latter moves freely in the opening direction.

In the unlocking position, responsive to the pull on the pull tab, the end 28 of the arm 30 of the locking member is pressed toward the bottom or rear face of the slide fastener stringers s, s, whereby the slide fastener stringers and the slide fastener elements f, f are bent out from the normal path and position. The forces derived from the tendency of the slide fastener stringers and slide fastener elements to resume the normal path and position move the locking member back to its locking position as soon as the pull on the tab is released. This self-locking tendency makes the slider of the present invention an automatic lock slider. The backward or return movement of the locking member to the locking position is accomplished by forces exerted on the end 28 (area of application) of the locking member arm 30. These forces comprise a frictional force, being effective during the operation of the slider and being due to the sliding movement of the slide fastener elements relative to the area of application, and a direct pressure, the latter being due to two different kinds of resiliency of the slide fastener now to be described.

According to our Patent No. 2,360,437, use is made of the slide fastener resiliency due to a deflection along a line transversely of the slide fastener (flexural force of the slide fastener). For this purpose a depression is provided in the slider body opposite the area of application. In said patent, it is disclosed that with such depression or concavity the stringers are caused to bend out of the normal path whereby the deflected slide fastener elements engage the area of application with an increased pressure. In the construction of the present invention, the opening 16 takes the place of the depression or concavity described in the said patent. The slide fastener stringers are bent out into the opening 16, and consequently the slide fastener elements, due to the tendency of the slide fastener to straighten out, contact the area of application with increased force.

According to this invention use is also made of the tendency of interlocked slide fastener elements to straighten out when forcibly flexed along the longitudinal center line of the slide fastener, that is to say, when flexed rotationally about said line. This tendency (rotational force of the slide fastener) additionally helps increase the direct pressure. The rotational deflection is produced by the shape of the end 28 of the locking member, the inner face of which is reversely curved from the medial plane thereof as best shown in Fig. 10B. The slide fastener elements when moving in the direction of the arrow X (Fig. 1), while the slider moves in the opposite direction Y to open the slide fastener, are forced to flex about the longitudinal center line of the slide fastener. In Figs. 10A, 10B and 10C, the course of this rotational deflection is illustrated schematically. In moving the slider in opening direction or in the direction of the arrow Y, the end 28 of the locking member arm 30 comes into contact with the rear face of the oppositely moving slide fastener elements. In Fig. 10A, two such inter-engaged slide fastener elements f, f are shown while approximately

coinciding with the plane of the line 1 of Fig. 1. The slide fastener elements in this position lie horizontally in the slide fastener channel C and are in full contact with the rear slider half 12. When the slider is moving along it will contact the slide fastener elements in the plane of the line 2 of Fig. 1. From Fig. 10B, it will be seen that in this position two adjacent interlocked elements are raised in the channel C whereby the head ends of the elements are raised to a much greater extent than are the leg ends. The raising action is performed, as is most clearly shown, by the arm 30 of the locking member. In Fig. 10C, illustrating the position along the line 3 of Fig. 1, two slide fastener elements are shown as again lowered in the channel but separated by the arm 30 which at that place forms a continuation of the slider neck.

The Figs. 10A, 10B, and 10C are explanatory of the force due to the rotational flexure of the slide fastener stringers while the locking member is in unlocking position. However, attention is called to the fact that provision may be made for rotational flexure of the slide fastener stringers with the locking member in locking position. Such constructional feature has the advantage that the force caused by the rotational turn of the slide fastener elements may be sufficient to keep the slider locked in case the latter is used in an upside-down position where the dependent pull tab gravitationally tends to unlock the slider, or when used under similar conditions.

Thus the direct pressure exerted on the area 35 of application at 28 of the locking member by the slide fastener stringers is due to flexing of the slide fastener stringers along a line transversely of the length of the slide fastener and to flexing along a medial line longitudinally of 40 the slide fastener.

In describing the exemplification of the invention as shown in Figs. 1-10C, it should be stressed that the slide fastener elements while sliding in the slider channel not only produce 45 friction at the area 28 but also at the area 28' (Figs. 1 and 7). The area 28' is on that part of the arm 30 which crosses the slider channel. Since the locking member is so disposed that said part of the arm 30 crossing the slider channel forms a continuation of the slider neck, the slide fastener elements contact both the area 28 and 28'. Accordingly, the rear side walls, as well as the head ends of the slide fastener elements, come into frictional contact with the locking member. This structure thus improves the self-locking qualities of the slider and also results in a smoother closing movement, the latter advantage being due to the fact that slide fastener elements, when moving in the directions 55 of the arrows Z in Fig. 2, strike against the locking member and tend to keep same in unlocking position. The resultant force applied at both areas of application 28 and 28' may be any one of the single forces, such as, frictional force, 60 flexural force, rotational force, or any combination of these single forces. The slider is preferably constructed so as to obtain as full an effect of all the forces as possible.

When the slide fastener stringers are subjected to a cross pull, the slide fastener elements are forced in the direction of the arrow X, and the slide fastener elements in turn force the locking member towards the fulcrum 20. The effect of raising the position of this fulcrum by means of 75 the lug 18, which may be termed a buttress ful-

crum, is to produce a strong vertical component force tending to hold the locking teeth 26, 26' in engagement with the slide fastener elements when such a cross-pull takes place. Accordingly, the buttress fulcrum is operative when the slider is locked against cross-pull or other fastener opening forces. At this time the fulcrum 23, which may be termed the base fulcrum, is inoperative. When the end 28 of the locking member arm 30 is pressed downward by the slide fastener stringers, the under surfaces 22 of the locking member come into contact with the front surface 25 of the slider and the locking member is free to rock about the fulcrum 23. The base fulcrum 23 is, therefore, operative during the transition of the locking member from the unlocking to the locking position. The base fulcrum is preferably not raised, this in order to insure the movement of the locking teeth substantially perpendicular to the travel of the slide fastener stringers. While the fulcrum 23 is operative, the buttress fulcrum is inoperative (in fact, there may be no contact at all at 20).

In Fig. 11, the application of the invention to a welded slider type is shown. This modified constructional form is similar to the construction of Figs. 1 to 10C. Two slider halves 56 and 58 are secured together by being spot welded at their wide ends at 60. The locking member 62, which may be manufactured in any suitable way, is provided with only one tooth 64 and is loosely supported by a lug 65 on the front slider half 56. In the construction here illustrated, the two fulcra previously described lie in the terminus 61 of the lug 65. The assembly of the parts of the slider is carried out by welding the slider halves together and by putting the locking member into place through an opening 66 in the lower slider half. The locking member, when projected upon the area of the opening 66, being larger than said area, is inserted in a curve. The pull is attached to the locking member preferably after inserting same into the slider. The locking member 64 is shown in full lines in the unlocking position and in dash-dotted lines in the locking position. The locking member is provided, as before, with an application arm 68 operating as described with the structure of Figs. 1 to 10C.

The construction and operation of the automatic lock slider of our present invention will in the main be fully apparent from the above detailed description thereof. In these structural forms of our lock slider, the locking member is so disposed and formed as not to interfere with the pin member of a separate bottom stop or with long top stops entering the slider channel. The arms of the lever locking member act on opposite sides or faces of the stringers, the area of application facing the rear side and the locking tooth or teeth the front side of the slide fastener stringers. The area of application is just behind and, therefore, in effect is a continuation of the neck or diamond of the slider and is localized along the longitudinal median region of the slider. This part of the locking member is thus in a non-interfering position and is located to exert the proper forces in both direction and amount on the operation of the locking means. Spacedly separated fulcra, one for operation in the locking condition and the other for operation in the unlocking condition are desirably provided; the buttress fulcrum is located away from the stringers to assist the locking condition and the base fulcrum is located relatively near the stringers to assist the unlocking condition. The locking

member is desirably provided with a plurality of application areas, one for contacting the faces of the elements and the other for engaging the heads of the elements. All of the improved results described are thereby achieved.

We have shown our invention in preferred embodiments; and it will be understood that many changes may be made in the construction and arrangement of the parts thereof without departing from the spirit of the invention defined in the following claims.

We claim:

1. An automatic lock slider for slide fasteners comprising a slider having a slider channel for the slide fastener stringers and a locking member mounted on the slider, said locking member consisting of a two-armed lever fulcrumed on the slider and having both of its arms projecting into the slider channel, one arm of the lever having a locking tooth and the other arm having a point of lever application, the locking tooth and point of lever application extending into the channel on opposite sides or faces of the stringers in said channel, the fastener elements on said stringers engaging the point of lever application causing the locking lever to rock on its fulcrum and move the locking tooth into engagement with another fastener element on the stringers and thus automatically lock the slider, and means on said lever operative for rocking the lever in its opposite direction to disengage the locking tooth and unlock the slider.

2. The automatic lock slider of claim 1 in which the lever is fulcrumed on the front of the slider, its locking tooth extends into the slider channel at the front of the slider and its point of application extends into the slider channel at the rear of the slider.

3. The automatic lock slider of claim 1 in which the lever is fulcrumed on the front of the slider, its locking tooth arm extends into the slider channel at the front of the slider and its other arm extends into the slider channel at the rear of the slider.

4. The automatic lock slider of claim 1 in which the lever is fulcrumed at the front of the slider, its locking tooth arm extends into the slider channel at the front of the slider and its other arm extends into the slider channel at the rear of the slider and is localized along a longitudinal medial region of the slider.

5. The automatic lock slider of claim 1 in which the said other arm of the lever is localized along a longitudinal medial region of the slider.

6. An automatic lock slider for slide fasteners comprising a slider having a front wall and a rear wall secured together at one end to form a neck and having a slider channel for the slide fastener stringers, and a locking member mounted on the slider, said locking member consisting of a two-armed lever fulcrumed on the slider at its neck end and having both of its arms projecting into the slider channel, one arm of the lever having a locking tooth and the other having a point of lever application, the locking tooth arm and point of lever application arm extending into the channel on opposite sides or faces of the stringers in said channel, with the latter arm localized to form a continuation of the slider neck, the fastener elements on said stringers engaging the point of lever application causing the locking lever to rock on its fulcrum and move the locking tooth into engagement with another fastener element on the stringers and thus automatically lock the slider, and means on said lever opera-

tive for rocking the lever in its opposite direction to disengage the locking tooth and unlock the slider.

7. The automatic lock slider of claim 6 in which the lever is fulcrumed at the front of the slider, its locking tooth arm extends into the slider channel at the front of the slider and its other arm extends into the slider channel at the rear of the slider and is localized along a longitudinal medial region of the slider.

8. An automatic lock slider for slide fasteners comprising a slider having a front wall and a rear wall secured together at one end to form a neck and having a slider channel for the slide fastener stringers, and a locking member mounted on the slider, said locking member consisting of a two-armed lever fulcrumed on the slider and having both of its arms projecting into the slider channel, one arm of the lever having a locking tooth and the other arm of the lever having a point of lever application, the said other arm of the lever being localized along a longitudinal medial region of the slider and forming a continuation of the slider neck, the fastener elements on said stringers engaging the point of lever application causing the locking lever to rock on its fulcrum and move the locking tooth into engagement with another fastener element on the stringers and thus automatically lock the slider, and means on said lever operative for rocking the lever in its opposite direction to disengage the locking tooth and unlock the slider.

9. The automatic lock slider of claim 8 in which the lever is fulcrumed on the front of the slider at its neck or upper end, the locking tooth extends into the slider channel at its lower end and the point of application extends into the slider channel in a region intermediate said ends.

10. The automatic lock slider of claim 1 in which said other arm is shaped medially thereof and of the slider to flex the stringers rotationally about a medial longitudinal line as the stringers pass through the slider in engagement with said arm.

11. The automatic lock slider of claim 1 in which said other arm is reversely curved from a medial plane thereof to flex the stringers rotationally about a medial longitudinal line as the stringers pass through the slider in engagement with said arm.

12. An automatic lock slider for slide fasteners comprising a slider having a slider channel for the slide fastener stringers and a locking member mounted on the slider, said locking member consisting of a two-armed lever fulcrumed on the slider and having both of its arms projecting into the slider channel, one arm of the lever having a locking tooth and the other arm having a point of lever application, the locking tooth arm extending into the slider channel at the front of the slider on one side or face of the stringers and point of lever application arm extending into the channel at the rear of the slider on the opposite side or face of the stringers in said channel, the fastener elements on said stringers engaging the point of lever application arm causing the locking lever to rock on its fulcrum and move the locking tooth into engagement with another fastener element on the stringers and thus automatically lock the slider, and means on said lever operative for rocking the lever in its opposite direction to disengage the locking tooth and unlock the slider, the said other arm being shaped medially thereof and of the slider to flex the

stringers rotationally about a medial line as the stringers pass through the slider in engagement with said arm.

13. The automatic lock slider of claim 12 in which the slider is provided with a front wall opening, the said locking member being movable in said opening, and in which engagement of the slide fasteners with said other arm flexes the stringers transversely of their length for movement into said opening.

14. The automatic lock slider of claim 1 in which the lever is fulcrumed on the front of the slider, its locking tooth extends into the slider channel at the front of the slider and its point of application extends into the slider channel at the rear of the slider, and in which the slider is provided with a front wall opening, the said locking member being movable in said opening, and in which engagement of the slide fasteners with said other arm flexes the stringers transversely of their length for movement into said opening.

15. The automatic lock slider of claim 1 in which the slider is provided with a double fulcrum seat for the locking member, one operative when the slider is moved to open said slide fastener stringer by a cross-pull and the other operative when said locking tooth is seated against a fastener element to lock the slider.

16. The automatic lock slider of claim 1 in which the slider has a front wall provided with two spaced fulcrum seats for the locking member, one fulcrum seat comprising a buttress member on said front wall operative when the slider is moved to open said slide fastener stringers by a cross-pull, and the other fulcrum seat comprising a base member on said front wall operative when the locking tooth is seated against a fastener element to lock the slider.

17. The automatic lock slider of claim 8 in which the slider has a front wall provided with two spaced fulcrum seats for the locking member, one fulcrum seat comprising a buttress member on said front wall operative when the slider is moved to open said slide fastener stringers by a cross-pull, and the other fulcrum seat comprising a base member on said front wall operative when the locking tooth is seated against a fastener element to lock the slider.

18. The automatic lock slider of claim 1 in which the said other arm has an extended region of lever application including a part for contacting the sides of the fastener elements and a part for engaging the heads of the fastener elements.

19. The automatic lock slider of claim 6 in which the rear wall of the slider is provided with an opening for insertion into the slider of the locking member.

WILLIAM MIKULAS.
